US00D529446S

(12) **United States Design Patent** (10) **Patent No.:** **US D529,446 S**
Su (45) **Date of Patent:** **** Oct. 3, 2006**

(54) **ELECTRICAL CARD CONNECTOR**

(75) Inventor: **Yu-Hung Su**, Tu-Cheng (TW)

(73) Assignee: **Cheng Uei Precision Industry Co., Ltd.**, Taipei Hsien (TW)

(**) Term: **14 Years**

(21) Appl. No.: **29/252,509**

(22) Filed: **Jan. 24, 2006**

(51) **LOC (8) Cl.** **13-03**

(52) **U.S. Cl.** **D13/147**

(58) **Field of Classification Search** D13/133, D13/146-147, 149, 154, 184; D14/432-436, D14/438; 439/64, 79, 159-160, 326, 492, 439/496, 607-610, 630-631, 862

See application file for complete search history.

(57) **CLAIM**

The ornamental design for an electrical card connector, as shown and described.

DESCRIPTION

FIG. 1 is a perspective view of an electrical card connector showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
